UNITED STATES PATENT OFFICE.

ALBERT EDWARD AINSLIE, OF BRASHEAR, MISSOURI.

REMOVABLE CAP FOR OIL-CANS.

1,116,968.

Specification of Letters Patent. Patented Nov. 10, 1914.

Application filed December 1, 1913. Serial No. 804,074.

To all whom it may concern:

Be it known that I, ALBERT E. AINSLIE, citizen of the United States, residing at Brashear, in the county of Adair and State 5 of Missouri, (whose post-office address is Brashear, Missouri,) have invented certain new and useful Improvements in Removable Caps for Oil-Cans; and I do declare the following to be a full, clear, and exact 10 description of the invention, such as will enable others skilled in the art to which it appertains to make and use the same.

This invention relates to improvements in removable caps adapted to be applied to the 15 spouts of oil cans of common construction and its main object is to provide a simple, strong and effective device of the character described which need only be formed in two parts.

20 With the above and other objects in view, the invention resides in the structure herein described and claimed and shown in the drawings wherein:—

Figure 1 is a side elevation of an oil can 25 showing my improved cap applied to the spout thereof; Fig. 2 is a similar view, on an enlarged scale, of a portion of the can; and Fig. 3 is a perspective view of the resilient fastening member for the cap.

30 In the accompanying drawings, I have shown an oil can 1 of ordinary construction being provided with the usual spout 2. Although forming no part of the present invention, these parts closely coact therewith.

35 Coming now more particularly to details, the numeral 3 designates broadly a coil spring which as shown, has its lower end reduced as at 4 for a purpose to appear. The free upper end of the wire forming the 40 spring 3 is bent upwardly as at 5, formed with a hook 6, then extends downwardly and to the opposite side of the spring where it is given a plurality of coils 7 around the upper convolution of the spring 3. This end 45 then extends upwardly from the coil 7, is formed into a hook 8 and then projects downwardly and is secured at 9 at a point above the spring 3.

A cap 10 having a depending flange 11 50 and being provided with a packing 12 on its inner side is adapted to seat over the open end of the spout 2. Said depending flange is provided with oppositely disposed

openings 13 through which pass the hooks 6 and 8 carried by the spring 3. 55

In practice, the reduced end 4 of the spring 3, is made of slightly less diameter than the diameter of the spout to which it is to be applied, while the upper portion of the spring 3 is of considerably greater diameter than the spout 2. Thus it will be seen that by unwinding the coils of the spring 4 to a proper extent, said spring may be slipped over the spout 2 and on account of its size, it will securely hold the device 65 upon said spout 2. It will then be obvious that the upper portion of the spring 3 is free to expand when it is desired to remove the cap 10.

Although I have shown the retaining and 70 expansion springs and the vertical arms of my device as formed of one piece of wire, it will be obvious that I need not be limited to this construction.

The caps and retaining springs may be 75 formed in any number of sizes for application to different sized can spouts but I find that by manufacturing them in three sizes, they will accommodate most cans on the market. 80

What I claim is:

A removable closure for can spouts comprising a cap having oppositely disposed apertures in the side walls thereof, a coiled spout-encircling spring composed of a single 85 strand of wire coiled to form a larger and a smaller end, the small portion being of uniform diameter throughout, said wire being extended longitudinally at opposite sides of the outer convolution of the larger portion and bent to form loops provided at their outer ends with hooks, the outer terminal of said wire being coiled around the outer convolution of the larger portion of the coil and then around the portion connecting the hook-carrying loops, said hooks being adapted to detachably engage the apertures in the side walls of the cap. 90

In testimony whereof I have hereunto set my hand in presence of two subscribing witnesses. 100

ALBERT EDWARD AINSLIE.
